TOURNIQUET

Henry L. Chenery, Portland, Maine

Application October 30, 1933, Serial No. 695,814

6 Claims. (Cl. 128—327)

The invention hereinafter to be described relates, in general terms, to tensioning and locking devices for straps and belts. While applicable for a wide variety of purposes my invention 5 will, in the present instance, be illustrated and described in connection with its use as a tourniquet, a device employed to stay the flow of blood from a wound in a person's leg or arm.

Tourniquets are what might be called first aid 10 implements and as such are frequently, in fact more often than not, used by novices. For this reason these devices should be simply made, easy to apply and operate, and capable of fulfilling all demands and requirements of an emergency in- 15 strument of this character.

In mounting a tourniquet on an injured member it should be placed near the wound on the side nearer the heart and the constriction of the flesh, brought about by tightening the strap, 20 should be of such strength and intensity as to fully stop the loss of blood through the wound.

In my present invention there are, among others, several features which I will point out as being of essential consequence in its operation, as 25 upon the satisfactory performance of a first aid appliance often depends the life of an accident victim.

1. There are no complicated and difficult-to-understand manipulations of straps and levers 30 when applying my tourniquet to a wounded arm or leg. The first or primary tension is made with as little difficulty as donning a body belt or fastening a skate strap. This is of utmost importance, as speed in applying the device will 35 often prevent a person bleeding to death.

2. The secondary or final tightening of the strap is accomplished in as simple a manner as the first operation and involves swinging a toggle arm, on which one end of the strap is permanently attached, from one end of the bed-frame to 40 its opposite end.

3. By employing a swinging toggle-arm the axis of which advances along the bed-frame as the toggle-arm itself is swung from one end to the 45 other of the bed-frame, actuation of the parts to effect the secondary constriction of the body is made vastly easier than if the two members were pivotally connected and the same amount of secondary take-up or strap movement procured in 50 each instance, the advantage in leverage in the first instance accounting for this.

4. The very convenient facilities for releasing the free end of the belt to procure, in infinite degrees, any desired amount of relaxing of the 55 secondary constriction.

The character of the invention may best be understood by reference to the description found in the following specification when taken in connection with the accompanying drawing disclosing an embodiment which, at the present time, I consider preferable to other possible forms in which the invention might be carried out.

In the drawing—

Fig. 1 is a plan view of my tourniquet showing the strap binding an object under primary con- 10 striction;

Fig. 2 is the same, except that the toggle-arm has been swung to the opposite end of the bed-frame, giving the strap its secondary constriction movement;

Fig. 3 is a section on line 3—3, Fig. 1;

Fig. 4 is a section on line 4—4, Fig. 2;

Fig. 5 is a section on line 5—5, Fig. 3;

Fig. 6 illustrates the method of releasing the free end of the strap to relax in any amount de- 20 sired the secondary constriction;

Fig. 7 is a perspective view of the strap-locking element;

Fig. 8 is a plan view of the toggle-arm, and

Fig. 9 is an alternative method of construct- 25 ing the strap-carrying cross-bar of the toggle-arm.

Similar reference characters are employed to identify like parts in all views of the drawing.

Referring to the drawing, 1 is the bed-frame of 30 the tourniquet and 2 the U-shape toggle-arm used in association therewith. The bottom face of the bed-frame is preferably slightly curved so that it may accommodate itself to the rounded 35 contour of the member upon which it is adapted to be mounted.

The bed-frame has two end cross-tie members, 3 and 4, the former serving to prevent the strap being displaced from between the sides of the bed-frame, but more particularly to complete the 40 rectangular structure and provide strength and rigidity therefor.

The cross-bar 4 besides functioning in the same capacity on its particular end as does the cross-bar 3 on the opposite end of the bed-frame 45 has a further duty to perform which will herein-after be fully disclosed.

On the top surfaces of the sides of the bed-frame 1 are gear tooth racks 5, operating, respectively, in which are two gears 6, one on and made 50 integral with each of the branches 2a of the toggle-arm 2; and projecting outwardly from each gear is a gudgeon 7.

Secured to each side of the bed-frame 1, by screws 8, is a plate 9 having a longitudinally dis- 55

posed slot 10 in which the gudgeon 7 operates as the gear travels forwardly and backwardly along the rack. On the top of each plate is an inwardly extending shelf 9a, serving as a shield to cover the gear and prevent a person's hands coming into contact therewith.

Interconnecting the sides 2a of the toggle-arm, and passing through the looped end Sa of the strap S, is a strap-carrying bar 11, one end of which is screw threaded into one side of the toggle-arm. This permits of removal of the bar in case the strap needs to be renewed.

It is possible, of course, to make the plate 9 integral with the bed-frame. In this case a slight modification in the construction of the strap-carrying bar is desirable, if not necessary.

In Fig. 8, showing a plan view of the toggle-arm, there is shown in dot and dash lines the outlines of the two legs on the bottom ends of which the gears 6 are mounted. In the integrally made bed-frame and plate, assembly difficulties arise in placing the toggle-arm with the gears engaging the racks. It is therefore necessary to spring the legs of the toggle-arm inwardly sufficiently to pass the gears between the overhanging guards 9a (the toggle-arm being held vertically in performing this operation). The legs of the toggle-arm may then be sprung outwardly, seating the gears in the racks; but the act of springing these legs inwardly has developed a "set" to the metal which cannot easily be taken out. So, preferably, when the parts are designed as just set forth, I employ a spacer tube 12 which forces the legs outwardly so that the gears are in perfect alignment with the racks. A bolt 11a secures the parts rigidly together, as is shown in Fig. 9.

A finger-hold 2b on the toggle-arm provides means by which to grasp the latter in the swinging operations.

In two oppositely disposed holes 13 in the sides of the bed-frame 1 is positioned a bar 14, one end preferably having a nick 14a serving as a key to lock the bar in one of the holes 13 and prevent its rotating therein.

Revolutely disposed on the bar 14 is a strap-locking pawl 15 having serrations 15a on its face. The cross-tie member 4 has a flat, inclined face 4a over which the strap S is drawn in making the primary constriction and on which it is locked against retraction movement by the pawl 15.

A spring 14a, one end of which is secured to the bar 14 and the other end disposed on the top side of the pawl, acts to maintain a constant yielding pressure of the pawl against the strap S. A finger-hold 15b serves as means to disengage the pawl from the strap when it is desired to release the free end of the strap to procure a reduced constriction pressure.

In this connection it might be well to state that in medical practice it has been found that it is dangerous to too greatly prolong the extreme constriction pressure, as, in case this is done, mortification or gangrenous conditions set in, causing serious and sometimes fatal consequences. It is, therefore, necessary to relax the extreme constriction pressure somewhat, and instead of swinging the toggle-arm backward into some intermediate position on the bed-frame to accomplish the above object, I prefer to attain this end by simply relaxing the free end of the belt or strap sufficiently to permit resumption of circulation in the smaller blood-carrying vessels, which, it may be, were not ruptured in the accident but in which the blood was prevented from

circulating when the extreme constriction pressure was applied to the member.

The method pursued in effecting a slackening of constriction pressure in my tourniquet device is graphically disclosed in Fig. 6 of the drawing. 5

While grasping the free end of the strap S between the forefinger and thumb of one hand and holding the strap taut, the pawl 15 is released from engagement with the strap by the other hand. The strap will now recede in the direction 10 of the arrows, reducing the pressure in any amount desired. The release of the strap is in reality a snubbing operation and is under perfect control of the operator who may, if he chooses carry out the releasing operation with one hand. 15

Fig. 6 also illustrates the manner in which the length of the strap which is added to the main binding portion to effect a reduction in constriction pressure is determined.

It will be observed by reference to the drawing that the thumb and forefinger grasping the free end of the strap are spaced a distance "x" from the end of the toggle-arm finger-hold 2b. Now as the strap is released, the thumb and finger, still grasping the strap, will move forwardly 25 with the strap until they abut on the portion 2b. At this point the pawl is allowed to again engage the strap, holding the pressure against further reduction. Thus the distance "x" is the determining factor and establishes a quick and sufficiently accurate gauge in the pressure-reduction operation. It is obvious, too, that the distance "x" may be one-eighth, one-half, three-quarters—in fact any measurement or length of strap which it is desired to add to the body-binding 35 portion thereof. In other words, the pressure-reduction process may be accomplished by a strap release almost infinite in its range.

Reverting to a consideration of the method of procuring the secondary constriction of the body 40 being bound, and with particular reference to Figs. 3 and 4 of the drawing, attention is called to the fact that I do not employ a pivotally mounted swinging element in my tourniquet device. In contrast, my construction involves what might 45 be called a travelling fulcrum obtained by gear-teeth the ends of the two branches of the toggle-arm and placing the gears in engagement with a stationary gear-tooth rack over which the gears travel simultaneously with the swinging 50 movement of the toggle-arm.

With this method of tightening the strap still further, after the preliminary binding of the body by the primary constriction has been accomplished, I can quite materially reduce the length 55 of the work arm, that is, the distance from the element 11 to the element 6; and with the power arm, or the distance from the element 2b to 6, largely in excess, as to length, of the work arm, a preponderance in leverage favoring the power 60 arm makes for ease in operating the toggle-arm in tightening the strap to obtain extreme constriction.

Now, to obtain the same amount of strap-tightening movement with a lever or crank arm directly pivoted to the bed member would necessitate positioning the bar 11 considerably further away from the pivotal point of the lever than is the case with my improved construction. Furthermore, it would require a greater manual effort to swing the lever and would also entail a loss of forward movement of the strap when the lever, which in reality is a crank, approached and passed over the dead center line.

In the present invention the strap is still being 75

tightened even when the toggle-arm is passing over the dead center line, as the geared fulcrum is continuously forcing the toggle-arm forwardly.

In operation, the instrument is laid on the injured member on the side of the bleeding wound nearer the body or torso of the accident victim, usually over the clothing he is wearing. The free end of the strap is passed around the member and reeved into the tourniquet between the locking pawl and the cross-bar 4 and given a pull of ordinary tensioning effort, the pawl locking the strap at this time. This gives what I call the primary constriction.

Next, the toggle-arm is grasped by the fingers of either hand and swung over from the position in which it is shown in Fig. 3 to that in which it is depicted in Fig. 4. This brings the tightening effort to what I designate as the secondary constriction pressure, and this is maintained until the time for relaxing a portion of this last constriction arrives, this operation having been hereinbefore described.

After the toggle-arm has been swung into full constriction position, as seen in Fig. 4, it will, by reference to this figure, be observed that the looped end 5a of the strap, seats firmly on the top of the pawl 15, and is maintained in this position due to the fact that the line of draft or pull of the strap from the element 11 to the element 3 lies in a plane much below the fulcrum point of the toggle-arm.

The present invention embodies all the essential characteristics of a first aid tourniquet, including simplicity, ease in applying and facile in operation. With slight modification in structure it may be used for other purposes.

What I claim is:

1. A tourniquet comprising a bed-frame having two longitudinally extending side portions, a gear-tooth rack on each of the side portions, a bifurcated, swingingly mounted toggle-arm, a gear on the end of each of the bifurcated portions of said toggle-arm, said gears adapted, respectively, to mesh in the two said racks, and means, including a retainer element, to hold the gears in constant mesh with the racks, whereby in whatsoever angular position said toggle-arm is disposed, its fulcruming contact with the bed-frame is such as to prevent slipping longitudinally thereof.

2. A binding device having a constriction strap formed in a single turn around the bound body and the secured ends of which substantially meet when it is under full tension, comprising a bed-frame, a cross-tie member at one end of the bed-frame having a flat, inclined inner face, a pawl adapted to engage said flat face to lock the strap interposed in any one of various length-wise positions on the strap, a U-shape toggle-arm swingingly mounted on said bed-frame, a cross-bar on the toggle-arm on which the opposite end of the strap is looped and secured, means, including two gears and two racks, to progressively advance the fulcrum points of contact of the toggle-arm with the bed-frame while the toggle-arm is being rotated to tension the strap in secondary constriction, a protective guard disposed outwardly of each of said gears, and means to hold said gears against displacement from the racks.

3. A binding device having a strap therefor, comprising an arcuate bed-frame, a U-shape toggle-arm operating in association with and swinging from said bed-frame, means to advance the fulcrum point of said swinging toggle-arm

continuously and uninterruptedly along the bed-frame, simultaneously with the rotative movement of the toggle-arm, a longitudinally disposed retaining element on said bed-frame adapted to prevent displacement of the fulcrum 5 end of the toggle-arm therefrom, a bar on said toggle-arm on which one end of the strap is non-detachably secured, a locking pawl adapted to secure the free end of the strap to and in various strap-bound positions on the bed-frame, 10 and means on the locking pawl for disengaging it from the strap, whereby any degree or amount of reduction in the constriction pressure of the strap may be procured.

4. A tourniquet having a tensioning strap 15 therefor comprising a bed-frame having two side portions and two end portions, an upstanding plate disposed at each side of the bed-frame and having a longitudinal slot therein, a gear guard extending inwardly from the top of said plate, a 20 gear-rack on the upper side of each of said side portions of the bed-frame, a rotatable, U-shape toggle-arm, a gear on each branch of said toggle-arm, said gears adapted to operate, respectively in the said racks, beneath the gear guards, a 25 gudgeon extending outwardly from each of the gears into the respective slots in the plates, for the purpose of holding the gears in correct mesh with the racks and prevent displacement of the gears from off the racks, and a cross-bar on said 30 toggle-arm on which one end of the strap is secured, said cross-bar being so disposed that when the toggle-arm is swung forwardly and into the full secondary constriction position, the axis of the toggle-arm lies outwardly of the plane in 35 which both the said cross-bar and the rearward end portion of the bed-frame lie.

5. A binding device having a strap for constricting a body upon which the device is adapted to be mounted, comprising a skeleton form, rec- 40 tangular bed-frame slightly arcuate in side elevation, a cross-bar at each end interconnecting the two side portions of the bed-frame, a gear-tooth rack on each of the said side portions, a rotatable, U-shape toggle-arm, a gear on the 45 end of each branch of the toggle-arm, said gears meshing, respectively, with the two racks, whereby during the period of rotation of said toggle-arm it is fulcrumed on the bed-frame at points thereon continually advancing or re-positioning 50 themselves in the direction of rotation of the toggle-arm, a strap-locking mechanism, including a pawl, operating in association with one of the said cross-bar members of the bed-frame to secure the free end of the strap after being tensioned to primary constriction, a spring yieldingly holding said pawl in firm contact with the strap, and a cross-bar on said toggle-arm on which the opposite end of the strap is looped and non-detachably secured, said cross-bar being so 55 disposed on said toggle-arm that, at the termination of the secondary constriction rotary movement of the toggle-arm, the strap loop on said cross-bar will abut on the top of said pawl acting supplementary to said spring in maintaining a strong engagement of the pawl with the strap while it is under extreme constriction.

6. A tourniquet having a binding strap therefor comprising a bed-frame, a toothed rack on each side bar of said bed-frame, a pawl operably 70 mounted on one end of said bed-frame adapted to lock the free end of the strap against retractive movement when said strap is under tension, a bifurcated, rotatable toggle-arm disposed on said bed-frame, segmental gears on the inner 75

ends, respectively, of the branches of said toggle-arm meshing with and fulcruming on the two said racks, a strap-carrying bar interconnecting the two branches of said toggle-arm, the opposite end of said strap being attached thereto, and a finger-hold by which the toggle-arm may be

swung to either tighten or loosen said strap as it encircles a body, the fulcrum point of the toggle-arm advancing in a continuous movement along the bed-frame during, and in the direction of, the swinging movement of the toggle-arm.

HENRY L. CHENERY.
